APPARATUS FOR RELEASING LOCKING
MECHANISM OF VAULT DOORSHarvey L. Henkel, Hamilton, Ohio, assignor to
Herring-Hall-Marvin Safe Company, Hamil-
ton, Ohio, a corporation of Florida

Application April 26, 1948, Serial No. 23,214

7 Claims. (Cl. 292—161)

1

This invention relates to a lock mechanism for doors of a compartment and more particularly to a mechanism for releasing the lock from within the compartment.

In some instances, persons have become accidentally trapped in vaults when no one capable of opening the door to allow their escape from the vault is present. Statutes in some localities require bank vault doors to be equipped with more than one lock as a safety measure. The key or combination of each of the locks will be in the possession of different individuals and it then becomes necessary for at least two people to be present when a vault is opened. It is, therefore, desirable to provide means for someone to open the door from within the vault.

It is an object of this invention to provide means for releasing the locking mechanism on the door of a vault from within the vault to allow the door to be opened.

Another object of this invention is to provide means for simultaneously releasing a plurality of locks in the door of a vault from inside of the vault to allow the door to be opened by a person trapped within the vault.

Another object of this invention is to provide a simple means for disengaging the bolts of a vault door from the wall of the vault while the locks of the vault door are in the locked position.

With these and other objects in mind which will become apparent in the following detailed description of the invention, this invention resides in lock bolts which may be displaced by the operation of a handle from within the vault to allow the bolt work of the vault door to be operated and the door opened.

In the drawings:

Figure 1 is a view in elevation showing the mechanism comprising this invention from within the vault with the inner cover plate of the vault door removed;

Figure 2 is a sectional view along the broken section line 2—2 in Figure 1 illustrating the structure for displacing the lock bolts;

Figure 3 is a sectional view, partially in elevation, along the sectional line 3—3 in Figure 1 showing the linkage between the handles on the vault and the bolt work of the door;

Figure 4 is also a sectional view, along the irregular section line 4—4 in Figure 1, illustrating the depressor bar in its raised position; and

Figure 5 is a vertical sectional view through the handles of the vault door along the section line 5—5 in Figure 1.

2

Referring to Figure 1, a door 1, partly broken away, is illustrated having a swinging edge 2. An edge plate 3 extends along the swinging edge 2 of the door and is apertured at 4 and 5 to support bolts 6 and 7 (hereafter called door bolts); and allow them to slide therethrough. Door bolts 6 and 7 engage recesses, not shown, in the wall of the vault to hold the door in a closed position. Door bolts 6 and 7 are free to slide horizontally

10 through the openings 4 and 5 in edge plate 3 and in their supporting hangers 8 and 9, respectively.

Vault door 1 is equipped with two locks 10 and 11, each having sliding bolt 12 (hereafter called lock bolts) which are shown in Figure 1 with their lock bolts 12 in the extended or locked position. These locks may be of any conventional type operated either by a key or by a dial for aligning tumblers within the lock. When the vault is unlocked from the outside, the lock bolts 20 12 are withdrawn into the locks 10 and 11 to a position allowing operation of the bolt work of the door.

A carrying bar 13 is secured to door bolts 6 and 7 by rivets 14 and 15, respectively. Carrying bar 25 13 abuts edge plate 3 when door bolts 6 and 7 are in the extended position illustrated in Figure 1. A pair of lock dogs 16 are actuated by carrying bar 13 and engage the lock bolts 12 when they are in the locked position to prevent movement of the carrying bar 13 in the manner hereinafter described. Carrying bar 13, dogs 16, and door bolts 6 and 7 comprise the bolt work of the vault door.

Referring to Figure 3, an arbor 17 passing through a bearing 17' in the front plate, indicated generally by 18, to the outside of the vault for the reception of a handle, not shown, is illustrated. An arm 19 secured to arbor 17 by a key or other suitable means to rotate integrally with the arbor, is held on the inner end of arbor 17 by a nut 20. A slot 21, best shown in phantom in Figure 1, is provided in arm 19 for engagement with a post 22 secured to the carrying bar 13. As the arbor 17 is rotated, arm 19 will engage post 40 22 to move carrying bar 13 when the locks 10 and 11 are in the unlocked position.

Referring to Figure 2, the dogs 16 are illustrated pivotally mounted on a post 23 secured to the front plate 18 of the vault. Dogs 16 have an actuating arm 24 in which a slot 25 is provided to receive a pin 26 extending from the front surface of carrying bar 13. A locking arm 27 extends substantially at right angles to actuating arm 24 from the hub of dogs 16 to a position adjacent lock bolts 12. As carrying bar 13 is moved,

pin 26 engages actuating arm 24 and dog 16 and rotates that dog around post 23 secured to the front plate 18 of the vault. If the lock bolts 12 are in the extended position, however, locking arms 27 of the dogs engage the sides of the lock bolt and prevent movement of carrying bar 13. Lock stumps 28 are provided adjacent lock bolts 12 on the side remote from the locking arms 27 for support of the lock bolts 12.

Lock bolts 12 each have an extension 30 extending from their ends for engagement with the locking arms 27 of dog 16. Latching members 30 are pivotally mounted on pins 31 passing through shoulders 32 on the lock bolts. One end of a torsion spring 33 on the spindle engages the extensions 30 and the other end engages the lock bolt 12 to hold the extensions in a normal position in which they are merely a longitudinal extension of the outer end of the lock bolts 12. The inner ends 34 of the extensions are curved as illustrated in Figure 2 to allow them to rotate on spindles 31 to a depressed position.

Referring to Figure 3, an inside arbor 35 is supported by a handle plate 36 secured to the edge plate 3. Arbor 35 passes through the inside cover plate, not shown, of the vault door and has a handle 37 attached thereto for operation of the releasing mechanism. Arbor 35 also passes through a slot 38 in the carrying plate 13 which allows the carrying plate 13 to slide relative to the arbor as the bolt work of the door is operated.

A cam, indicated generally by 39, is keyed to the end of arbor 35 remote from the handle 37 and is held in place by a nut 40. Cam 39 is substantially V-shaped and has an arm 41 with an aperture 42 for the reception of a post 43 secured to carrying bar 13. Aperture 42 is larger in diameter than post 43 to allow movement of the cam 39 before it engages post 43.

Cam 39 also has a beveled arm 44 integral therewith extending from the arbor 35 towards the hinged edge of the door. Arm 44 is beveled at 45 in the manner shown in Figures 3, 4, and 5 to actuate a depressor bar 46. Depressor bar 46 is spaced from the front plate 18 directly in front of the beveled arm 44 of cam 39. In the form shown in the drawings, depressor bar 46 is equipped with sleeves 47 slidable on studs 48 engaging the front plate 18. Compressed helical springs 49 between front plate 18 and depressor bar 46 urge the depressor bar towards the beveled arm 44 of cam 39.

Depressor bar 46 extends to a position adjacent the lock bolts 12 and is equipped with pins 50 extending from each of its ends over the latching members 30 of lock bolts 12. A channel plate 51 is secured to depressor bar 46 by any suitable means such as screw 52 directly below beveled arm 44 for engagement with that arm as arbor 37 is turned. A roller 53 journaled in the sides of the channel engages the beveled surface 45 of lever 39. Springs 49 lift the depressor bar 46 and consequently pins 50 to a normal position spaced above the latching member.

When the lock bolts 12 of locks 10 and 11 are in an extended position, the vault may not be opened by arbor 37. Any attempt to turn arbor 37 will result in dogs 16 engaging the extension 30 of the lock bolts 12 to prevent movement of the carrier bar. It is, therefore, necessary to unlock locks 10 and 11 before the vault can be opened from the outside.

If one is trapped within the vault, however, he may turn handle 37 to rotate arbor 35 and cam

39. The beveled surface 45 of cam 39 will engage roller 53 and depress the depressor bar 46 which is slidable on studs 48. The pins 52 at the end of the depressor arm bear against the upper surface of extension 30 and depress them to a position illustrated by the dotted lines in Figure 2 in which they will not engage the bolt work of the door. The structure could, of course, be modified to allow the cam 39 to displace the extension 30 in any direction to a position allowing movement of the bolt work.

The lost motion connection provided by opening 42 having a larger diameter than post 43 allows the carrying bar to remain stationary for a short period even though the arbor 45 is turned. Beveled surface 45 will then ride over the roller 53 to depress the depressor arm and displace the extensions before the post 43 bears against the walls of opening 42. Further rotation of the handle 37 will slide the carrying bar 13 away from the edge plate 3. Since door bolts 6 and 7 are secured to the carrying bar 13, those bolts are withdrawn from the recesses in the wall of the vault and allow the door to be opened. Any movement of carrying bar 13 will, of course, make it necessary to rotate dogs 16; however, since extensions 30 have been depressed before carrying bar 13 is moved, the locking arms 27 of dog 16 are free to move over the upper surface of extensions 30.

As the vault door is closed and locked, the outside handle connected to arbor 37 is turned to operate the bolt work and slide door bolts 6 and 7 into engagement with the recesses in the wall of the vault. As carrying bar 13 is moved to the position shown in Figure 1, the post 43 engages the opening 42 to rotate cam 39 to the locked position. Compressed helical springs 49 are then free to lift depressor bar 46 to a position spaced from the extensions 30 and torsion springs 33 hold the extensions in an extended position. There are, therefore, positive means provided to eliminate any possibility of extensions 30 remaining depressed to allow the vault to be opened from the outside when the locks 10 and 11 are in the locked position.

The release mechanism described herein is especially suitable for use in vault doors having more than one lock engaging the bolt work of the vault door. The novel mechanism simultaneously displaces the lock bolts of each of the locks and operates the bolt work to allow the door to be opened by turning a single handle on an arbor passing through the inside surface of the vault door.

Throughout the description of this invention, the structure has been described in relation to a vault door. Clearly, the invention may be employed in locking mechanism for the closure means of any compartment which may, on occasion, be opened from within.

The present invention has been described in detail in relation to a lock mechanism for doors of a compartment. It is to be understood that the invention is not limited to those details but is limited by the scope of the appended claims.

I claim:

1. Locking mechanism for the door of a compartment comprising door bolts carried by the door for engagement with a wall of the compartment, a carrying bar attached to the bolts and movable therewith, locks having lock bolts adapted to occupy a position obstructing movement of said carrying bar, a handle operable from within the compartment and connected with the car-

rying bar, a cam secured to the handle, and means actuated by the cam to move the lock bolts from their obstructing positions as the handle is turned in a direction to move the bar to disengage said door bolts from said wall.

2. In a door locking mechanism for a vault including boltwork movable to secure and release said door and locks having lock bolts, each lock bolt having an extension pivotally attached thereto, resilient means holding each extension in a normal position to obstruct movement of the boltwork, and means common to said extensions and including a handle operable from within the vault to displace the extensions from said obstructing position, and means operatively connecting the handle with the boltwork to move the same.

3. Locking mechanism for the door of a compartment comprising door bolts carried by the door for engagement with a wall of the compartment, a carrying bar attached to the bolts and movable therewith, dogs pivotally connected to the door and engaging said bar to be rotated by movement thereof, locks having lock bolts adapted to occupy positions to obstruct rotation of the dogs, a handle operable from within the compartment, means actuated by the handle for displacing the lock bolts from obstructing position to permit rotation of the dogs, and a lost motion connection between the handle and carrying bar to move said bar and disengage said door bolts after actuation of said means for displacing said lock bolts from obstructing position.

4. Locking mechanism for a vault door having boltwork and means outside the vault for operating the same, a plurality of lock bolts carried by the door and independently movable to positions into and out of engagement with the boltwork to respectively block and permit movement thereof, a common bar member engaging said lock bolts and movable to displace the same from their positions in engagement with the boltwork, and means including a cam engaging the bar and manually operable from within the vault for moving the bar to displace said lock bolts and permit movement of the boltwork.

5. In a locking mechanism for a vault door having boltwork, a plurality of independently operated locks on the door, each lock having a lock bolt adapted to be extended and retracted from the lock, an extension movably mounted on each lock bolt and having a position relative to the lock bolt to engage the boltwork when the lock bolt is extended to block door releasing movement of the boltwork, a member common to said

extensions and adapted to move the same out of engagement with the boltwork independently of movement of the respective lock bolts, means including a handle operable from within the vault and operatively engaging the boltwork to move the same, said handle also having an operative connection with said member to move said extensions out of engagement with the boltwork.

6. In a locking mechanism for a vault door having boltwork, a plurality of independently operated locks on the door, each lock having a lock bolt adapted to be extended and retracted from the lock, an extension pivotally mounted on each lock bolt and having a position relative to the lock bolt to engage the boltwork when the lock bolt is extended to block door releasing movement of the boltwork, a depressor bar common to and adjacent said extensions, resilient means urging said bar away from said extensions, a roller on said bar, a handle operable within the vault and carrying a cam engaging said roller to move the bar against said extensions and pivotally displace the same away from boltwork engaging position upon movement of the handle.

7. In a locking mechanism for a vault door having boltwork, a plurality of independently operated locks on the door, each lock having a lock bolt adapted to be extended and retracted from the lock, an extension pivotally mounted on each lock bolt and having a position relative to the lock bolt to engage the boltwork when the lock bolt is extended to block door releasing movement of the boltwork, a depressor bar common to and adjacent said extensions, resilient means urging said bar away from said extensions, a roller on said bar, a handle operable within the vault and carrying a cam engaging said roller to move the bar against said extensions and pivotally displace the same away from boltwork engaging position upon movement of the handle, and lost motion means operatively connecting the handle with the boltwork to move the boltwork to door releasing position after displacement of said extensions.
